US00D834743S

(12) **United States Design Patent** (10) **Patent No.:** **US D834,743 S**
(45) **Date of Patent:** **** Nov. 27, 2018**

(54) **SMOKING ARTICLE**

- (71) Applicant: **Altria Client Services LLC**,
Richmond, VA (US)
- (72) Inventors: **Christopher S. Tucker**, Midlothian, VA
(US); **Geoffrey Brandon Jordan**,
Midlothian, VA (US); **Barry S. Smith**,
Hopewell, VA (US); **Ali A. Rostami**,
Richmond, VA (US)
- (73) Assignee: **Altria Client Services LLC**,
Richmond, VA (US)
- (**) Term: **15 Years**
- (21) Appl. No.: **29/553,863**
- (22) Filed: **Feb. 5, 2016**

Related U.S. Application Data

- (63) Continuation of application No. 29/469,750, filed on
Oct. 14, 2013, now abandoned.
- (51) **LOC (11) Cl.** **27-01**
- (52) **U.S. Cl.**
USPC **D27/101**

(57) **CLAIM**

The ornamental design for a smoking article, as shown and
described.

DESCRIPTION

FIG. 1 is a left end, perspective view of a smoking article
showing our new design.

FIG. 2 is right end, perspective view thereof.

FIG. 3 is a side elevational view thereof, the other side being
a mirror image.

FIG. 4 is a left end elevational view; and,

FIG. 5 is a right end elevational view.

1 Claim, 3 Drawing Sheets
